US00D609864S

(12) **United States Design Patent**
Tsai

(10) **Patent No.:** **US D609,864 S**
(45) **Date of Patent:** **** Feb. 9, 2010**

(54) **BIRD FEEDING APPARATUS**

(75) Inventor: **Mao Bang Tsai**, Jidali Industrial Zone, Gonghe Village, Shajing Town, Baoan District, Shenzhen, Guangdong (CN) 518000

(73) Assignees: **Guang'an Zeng**, Shenzhen (CN); **Mao Bang Tsai**, Shenzhen (CN)

(**) Term: **14 Years**

(21) Appl. No.: **29/335,790**

(22) Filed: **Apr. 22, 2009**

(30) **Foreign Application Priority Data**

Jan. 19, 2009 (CN) 2009 3 0163207

(51) **LOC (9) Cl.** **30-03**

(52) **U.S. Cl.** **D30/127**

(58) **Field of Classification Search** D30/121, D30/124, 126-129, 133, 199, 110-112, 123, D30/125; 119/52.2, 51.5, 61.5, 57.8, 57.9, 119/52.3, 61.1, 531, 63, 428-435, 52.4, 55, 119/61.3, 69.5, 57, 76; 47/67, 83; 248/318; D11/164, 152; 211/128.1; D27/123; D6/495, D6/460, 461, 476, 405

Primary Examiner—Susan Moon Lee

(57) **CLAIM**

The ornamental design for a bird feeding apparatus, as shown and described.

DESCRIPTION

FIG. 1 is a front perspective view of the bird feeding apparatus;

FIG. 2 is a front elevational view of the bird feeding apparatus;

FIG. 3 is a rear elevational view of the bird feeding apparatus;

FIG. 4 is a left side elevational view of the bird feeding apparatus;

FIG. 5 is a right side elevational view of the bird feeding apparatus;

FIG. 6 is a top view of the bird feeding apparatus; and,

FIG. 7 is a bottom view of the bird feeding apparatus.
